UNITED STATES PATENT OFFICE

2,514,067

DISTRIBUTOR FOR CANS

Joseph L. Jackson and Eugene B. Tipton, Baltimore, Md., assignors to Continental Can Company, Inc., New York, N. Y., a corporation of New York

Application January 18, 1946, Serial No. 642,006

7 Claims. (Cl. 198—31)

1

The following specification relates to our invention of a novel distributor for cans and similar articles.

Mechanical handling of cans delivered by can closing machines necessitates movement of these cans by conveyers, runways or the like which may also serve the additional purpose of distributing or dividing the cans into a plurality of paths for subsequent manipulation such as labeling and packing. This handling of the closed cans usually depends upon movement of one can by another or an accumulation of cans moving in contact with each other.

It is an object of our invention to advance and distribute cans separately and individually without reliance upon motion being imparted by one can to another as is the case when they are pushed along a runway by pressure from cans in the rear.

Another object of our invention is to use a common means to effect not only the conveying of the cans independently, but also their distribution individually according to prior plan.

Incidental to the above purpose, it is our object to avoid using a star wheel as a sole reliance for primarily distributing the individual cans.

At the same time it is a further object of our invention to utilize the star wheel to insure that the cans clear the joint conveying and distributing means.

It is also a further object of our invention to utilize the star wheels as adjuncts in the disposition of the cans by providing that they supplement the action of the dividing rail.

These and other objects of our invention will be apparent from the following description of the preferred form of our mechanism as illustrated in the accompanying drawings in which:

Fig. 1 is a plan view of our improved distributor;

Fig. 2 is a side elevation of the same, and

Fig. 3 is a transverse vertical section on the line 3—3 of Fig. 1.

As illustrating the essential features of the invention embodied in our preferred form thereof, the accompanying drawings show, broadly, means to receive and convey cans individually into and through a station where they are individually diverted into separate runways according to prior plan.

The machinery is mounted upon a table 11 supported at one end on a pedestal 12 and attached at the opposite end to the apron 13 of a turreted can-closing machine, or the like. It is, of course, understood that such can-closing machine, not

2

forming part of the invention, includes means for discharging closed cans in independent and spaced order upon the table 11 where they are engaged successively for separate advance and distribution.

On the table 11 near the apron 13 are parallel spaced guides 14 and 15. These guides are adjustably clamped on the table to form a passageway suitably proportioned to receive cans or similar articles.

In the example illustrated, the passageway between the guides 14 and 15 receives a cylindrical can 16 resting upon one of its ends.

Guide 14 has an extension 17 while a similar extension 18 is attached to guide 15. Extensions 17 and 18 form side rails for two parallel adjacent runways 19 and 20 each of which permits the passage of cans 21, 22 after they have been apportioned between the adjacent runways 19 and 20.

A center rail 23 separates the runways 19 and 20 and has a tapering front edge or point 24.

The table 11 has a longitudinal central slot 25 in which a link conveyer chain 26 passes. Beneath the table at the pedestal end are a pair of aligned bearings 27, 27 which serve to receive a transverse shaft 28. Centrally of the shaft 28 is a sprocket wheel 29 keyed to rotate the shaft 28.

The sprocket wheel is driven by the chain 26 from a drive sprocket, not illustrated, suitably mounted beneath the table at the end nearer the closing machine. A shaft 29 journaled in the table 11 is vertically adjustable to carry a tensioning idler not shown. In this manner the chain 26 is constrained to pass horizontally and substantially in the plane in the upper surface of the table as shown in Fig. 2.

Suitably positioned along the links of the chain 26 are upstanding lugs 30, 31. These lugs are arranged in pairs with the lugs 30 in advance of the lugs 31. The lugs 30 in advanced position are alternately located on opposite sides of the chain 26 in the manner shown in Fig. 1.

Shaft 28 has a small bevel gear 32 keyed at each end. Matching bevel gears 33, 33 are keyed to the lower ends of vertical stub shafts 34, 34 suitably held in vertical journals 35, 35 of the bearings 27, 27.

Cover plates 36, 36 complete the housing of the gears 32, 33.

Suitably keyed to the upper ends of the shafts 34, 34 are star wheels 37, 38. As indicated in Fig. 3, the star wheels rotate in a plane spaced above the level of table 11 so that the cans which are be-

ing distributed are engaged at points above the end rims upon which they rest.

The star wheels 37 and 38 have suitable shields 40, 40 surrounding the portions outside of the side rails 17, 18.

Each star wheel consists of a hub 41 keyed to the shaft 34 and a plurality of equally spaced blades 42. These blades have downwardly extending peripheral flanges 43 as shown more particularly in Fig. 3. By this means, extended engagement is given the cans being distributed and advanced. Each star wheel has intervening pockets 45 between the adjacent blades 42. These pockets are rounded at the bottom to conform to the diameter of the cans being distributed. The forward edge of the pocket extends at an advanced angle with respect to the radius of the wheel. The advancing front wall has an inclination substantially coinciding with the side rail beneath which it rotates.

The rear edge of the pocket 45 advances to the rounded point 47 where the pocket meets the circular periphery of the star wheel.

The pocket 45 of one star wheel is set to rotate opposite the peripheral edge of the other star wheel. This is clearly indicated in Fig. 1. It will be observed that the peripheral edge of the star wheel thus forms a continuation of the center rail 23 in advance of its point 24.

Cans from the closing machine received from the apron 13 are delivered over the traveling conveyer chain 26. Each can, of course, is delivered separately and at spaced intervals of time. Each can 16 is picked up and advanced by the forward lug 30 of each pair arranged in echelon formation on the conveyer chain.

Thus the can is advanced along the passageway between the guides 14 and 15 and their side rail extensions 17 and 18.

As the can 16 comes to the flaring portion between the side rails 17 and 18, the lug 30 being at one side of the median line, gives the can a push to the opposite side so that it follows the flaring portion of either side rail 17 or 18, as the case may be. In this position, as shown by can 48, the rear lug 31 of the pair has engaged the periphery of the can. The can is then given an oblique push by the pressure from both lugs 30 and 31 jointly in the direction of the diverging portion of the side rail.

This movement continues until the can is substantially clear of the lugs 30 and 31. In this movement the rounded point 47 of the star wheel 37 as well as the peripheral face of the latter, insure the distribution of the can into the appropriate discharge runway 19 or 20. Can 49 is shown to have thus been distributed into the runway 19 and the pocket 45 of the star wheel 37.

It will be noted that flange 43 of the star wheel 37 is high enough to permit lugs 30 and 31 to pass underneath and around sprocket chain 29.

Further rotation of the star wheel brings the advancing edge 46 substantially beneath the side rail so that the rear edge of the pocket then serves to advance the can into the position shown at 21 and 22.

From this point, the cans pass along runways 19 and 20 either by gravity, pressure from behind or by the use of a moving belt as a bottom for the runway.

It is significant that the novel apparatus thus outlined operates on the cans or other similar articles separately. Further, each article is directed into the intended path in advance of its engagement with a star wheel. At the most, the

wheel gives only a final or supplementary push to the can in removing the latter from the incoming path and thereafter serves mainly to guide the can and finally to give it a straight-line push along the selected discharge passageway. The star wheel is also raised above the base rim of the can and thus clears the line of travel of the forwarding conveyer chain and its lugs.

The structure above described makes possible the advance separately of individual cans as received from a manufacturing or filling and closing machine and their distribution into two or more discharge paths according to prior plan. Variation in the size of the pockets in the star wheel, or in their number and arrangement will permit handling cans of different sizes and increase in the number of discharge paths. Accordingly these and other changes in size, form and arrangement of parts as well as materials and mechanical details are possible within the scope of the following claims.

What we claim is:

1. A machine of the class described having a passageway, two discharge passageways leading therefrom and having a common dividing rail, a conveyer running longitudinally through the center of the initial passageway to the dividing rail, and directing means on the conveyer and laterally of its center line to engage an article and forward it into a preselected discharge passageway.

2. A machine of the class described having a passageway, a discharge passageway leading therefrom and having a dividing rail axially of said first named passageway, a conveyer running longitudinally through the center of the initial passageway to the dividing rail, and a pair of upstanding lugs arranged in echelon on the conveyer for engaging an article and forwarding it into said discharge passageway.

3. A machine of the class described having a passageway, two discharge passageways leading therefrom and having a common dividing rail, a conveyer running longitudinally through the center of the initial passageway to the dividing rail, and pairs of upstanding lugs arranged in echelon and one lug of each pair on each side of the conveyer for engaging an article and forwarding it into a preselected discharge passageway.

4. A machine of the class described having a passageway, two discharge passageways leading therefrom and having a common dividing rail, a conveyer running longitudinally through the center of the initial passageway to the dividing rail, spaced pairs of upstanding lugs arranged successively in oppositely inclined echelons on the conveyer, each pair of lugs engaging an article and forwarding it into a selected discharge passageway.

5. A machine of the class described having a passageway with side walls, two discharge passageways having side walls with flaring portions connecting with the walls of the initial passageway, a common rail between said discharge passageways, a conveyer running longitudinally through the center of the initial passageway to the dividing rail, pairs of upstanding lugs each pair arranged in echelon on the conveyer for engaging an article and forwarding it along a flaring portion of one side rail and into the corresponding discharge passageway.

6. A machine of the class described having a passageway, two discharge passageways leading therefrom and having outer rails and a common dividing rail, a conveyer running longitudinally

through the center of the initial passageway to the dividing rail, pairs of upstanding lugs each pair arranged in echelon on the conveyer, and a star wheel rotating horizontally in each discharge passageway, said star wheels having peripheries overlying the conveyer in advance of the dividing rail and pockets of substantially the same depth as the width of the discharge passageway.

7. A machine of the class described having a passageway, two discharge passageways leading therefrom and having a common dividing rail, the forward end of the rail being raised above the floor of the passageways, a conveyer running longitudinally through the center of the initial passageway to a point beneath the dividing rail, lugs on the conveyer laterally of said dividing rail and projecting above the floor of the initial

passageway but beneath the dividing rail, and a star wheel rotating horizontally in each discharge passageway above the said lugs and substantially in the plane of the dividing rail.
